US0D1102999S

(12) **United States Design Patent** (10) Patent No.: **US D1,102,999 S**
(45) Date of Patent: ** Nov. 25, 2025

(54) **RADIATOR GRILLE FOR AN AUTOMOBILE**

(71) Applicants: **Hyundai Motor Company**, Seoul (KR); **Kia Corporation**, Seoul (KR)

(72) Inventors: **Joseph Springer**, Superior Township, MI (US); **Bradley J. Arnold**, Superior Township, MI (US)

(73) Assignees: **Hyundai Motor Company**, Seoul (KR); **Kia Corporation**, Seoul (KR)

(**) Term: **15 Years**

(21) Appl. No.: **29/946,289**

(22) Filed: **Jun. 7, 2024**

(51) LOC (15) Cl. **12-16**

(52) U.S. Cl.
